United States Patent Office

Des. 202,843
Patented Nov. 9, 1965

202,843

COMBINED WRITING INSTRUMENT AND KEY CHAIN

Benton Dales, 1 Forest Dunes, Covert, Mich.

Filed Aug. 6, 1964, Ser. No. 81,181

Term of patent 7 years

(Cl. D74—17)

FIG. 2

FIG. 1

FIG. 3

FIG. 4

FIGURE 1 is a perspective view of the combined writing instrument and key chain, in the writing position, showing my new design;

FIGURE 2 is a front elevational view thereof, in the stored position;

FIGURE 3 is a sectional view taken substantially along line 3—3 of FIGURE 2; and

FIGURE 4 is a front elevational view of the writing portion of the instrument showing my new design.

The sides not shown are substantially the same as those shown.

I claim:

The ornamental design for a combined writing instrument and key chain, substantially as shown and described.
